Henry J. Schmidt

UNITED STATES PATENT OFFICE

LOUIS LUDWIG, OF BROOKLYN, NEW YORK

ELECTRIC BLINKER

Application filed May 13, 1930. Serial No. 362,583.

The invention relates to blinkers for interrupting an electric current so that any electric lamp lit by the current will be caused to blink, or to be alternately switched on and off. The invention resides in the novel construction whereby the device may be connected on one of the wires in the circuit, and in the novel and compact arrangement and assembling of the various parts constituting the device. The object of the invention is to provide a blinker of simple, compact and inexpensive construction, which can conveniently be connected in any circuit and which will function with accuracy.

These and other objects and advantages will be readily understood from the following description and from the accompanying drawing of a preferred embodiment of which

Fig. 1 is a cross-sectional side view,

Fig. 2 a top view,

Fig. 3 another top view with part of the casing removed,

Fig. 4 a cross-sectional side view of a modification,

Fig. 5 an enlarged view of the end of the casing, and

Fig. 6 another enlarged view of the end of the casing showing a modification.

Referring first to Figs. 1, 2 and 3, the blinker consists of a lower casing 10 and an upper casing 11. These parts are made of insulating material and are provided with lugs 12, 13, 14 and 15 at their ends. A rectangular recess 16 is formed within the casings and these are held together by eyelets 17 and 18.

A thermostatic switch is located in the recess 16 and consists of a strip of insulating material 19 on which is mounted, by means of an eyelet 20 and a screw and nut 21 and 22, a strip of thermostatic metal 23. A contact point 24 is riveted in one end of the strip 23 and aligns with a contact point 25 which is mounted in the end of the adjusting screw 26. This screw is secured on the insulating strip 19.

A metal, connecting link 27 is secured to one end of the insulating strip by means of the adjusting screw and a similar link 28 is secured to the other end by means of the eyelet 20. These links are clamped between

the lugs 12, 13, 14 and 15 when the eyelets 17 and 18 are riveted and thus rigidly support the thermostatic switch.

A piece of asbestos 29 is wrapped around the thermostatic metal strip and upon this is wound a resistance coil 30, one end of which is connected to the link 27 and the other end to the link 28. The construction of the switch is such that under normal temperature the contact points 24 and 25 are disconnected. When the current is first turned on it passes through the link 28, resistance coil 30 and link 27, until, from the heat given up by the coil, the thermostatic strip curves and the points 24 and 25 contact. After which the current flows through link 28, thermostatic strip 23, adjusting screw 26 and link 27. After the strip cools the contact points disengage and the current again flows through the resistance coil. The timing of these alternations may be altered by adjusting the screw 26.

As already explained, the links 27 and 28 are secured between the lugs of the casings by means of the eyelets 17 and 18. The links are in electric contact with the eyelets and the eyelets are internally threaded. Screws 31 and 32 engage in the eyelets and the upper casing is counterbored so as not to expose the heads of these screws. The blinker is connected in the circuit by means of these screws, as plainly shown by the wires 33 and 34.

It will be seen that with the construction as just explained the switch may be fully assembled, tested and adjusted before being sealed in the casings. The modification shown in Fig. 4 differs somewhat in its construction. The casings and the method of assembling these are the same, but the insulating strip and the adjusting screw are omitted. In this case the thermostatic metal strip 35 is clamped between one end of the casings and a metal link 36 between the other end. It operates similar to the blinker first described. While it is stated that the casings 10 and 11 are constructed of insulating material, it will be readily understood that these parts may be constructed of metal and properly insulated from the switch 100.

mechanism as shown in Fig. 6. In this case insulating bushings 37 and 38, having shoulders 39 and 40 respectively, insulate the eyelet from the half casings, while insulating washers 41 and 42 insulate the part 27. The hole in part 27 fits the eyelet tightly.

Having described my invention, what I claim as new and wish to protect by Letters Patent is:

- 10 1. An electric blinker connectable to a single wire of an electric circuit consisting of, a casing formed of two halves, a thermostatic switch contained in said casing and insulated therefrom, the terminals of said switch supported between the ends of the half-casings and electrically connected with the means by which these are assembled, and said assembling means consisting of eyelets which form the terminals by which the device is connected in an electric circuit.
- 15 2. An electric blinker connectable to a single wire of an electric circuit consisting of, a casing made of insulating material and formed of two halves, a thermostatic switch contained in said casing, the terminals of said switch supported between the ends of the half-casings and directly connected with the metal fasteners by which these are assembled, and said metal fasteners consisting of eyelets which form the terminals by which the device is connected to a wire.
- 20 3. An electric blinker adapted to be connected to a single wire of an electric circuit and consisting of, a casing made of insulating material and formed of two halves, an adjustable thermostatic switch contained in said casing, the terminals of said switch supported between the ends of the half-casings and electrically connected with the means by which these are assembled, and said assembling means consisting of eyelets which form the terminals whereby the device is connected in an electric circuit.
- 25 4. An electric blinker adapted to be connected to a single wire of an electric circuit and consisting of, a casing made of insulating material and formed of two halves, a thermostatic switch contained in said casing, the terminals of said switch supported between the ends of the half-casings and electrically connected with the means by which these are assembled, and said assembling means consisting of internally threaded eyelets which in connection with screws inserted therein form binding posts for connecting the device in an electric circuit.

LOUIS LUDWIG.
